John F. Allan & Joseph Stewart, of Philadelphia, Pa.
Assignors to

Cresson, Stuart, & Peterson, of same place.

Letter Patent No. 654. Dated May 23d. 1834.

The schedule referred to in these Letters Patent, and making part of the same.

To all whom these presents shall come:

Be it known that we, John F. Allan, and Joseph Stewart, of Philadelphia in the County of Philadelphia, and State of Pennsylvania, have invented a new design for a Portable Range, and that the following is a full, clear, and exact description of the principle or character which distinguishes it from all other things before known, and of the usual manner of making, modifying, and using the same, reference being had to the accompanying drawings.

Fig. 1 is a front view of the front plate, illustrating the oven door and fire door.

Fig. 2 is a front view of the end plate.

These drawings illustrate our design for the portable range other parts of the same being plain and ornamental at pleasure.

What we claim as our invention is the design for Portable Range, as herein above illustrated and set forth.

And witness, -
